R. E. COX

SUCKER ROD COUPLING

Filed July 8, 1922

Inventor

R.E. Cox

By Watson E. Coleman Attorney

UNITED STATES PATENT OFFICE.

REGINALD E. COX, OF MEXIA, TEXAS.

SUCKER-ROD COUPLING.

Application filed July 8, 1922. Serial No. 573,706.

To all whom it may concern:

Be it known that I, REGINALD E. Cox, a citizen of the United States, residing at Mexia, in the county of Limestone and State of Texas, have invented certain new and useful Improvements in Sucker-Rod Couplings, of which the following is a specification, reference being had to the accompanying drawings.

10 This invention relates to improvements in coupling devices for the sucker rods of oil wells.

An important object of the invention is to provide a device of this character which 15 will permit ready rotation of the lower end of the sucker rod and which provides means for cushioning the movement of the sucker rod during the change of direction from up to down strokes.

20 A further object of the invention is to provide a device of this character which will permit relative rotation of the connected sections of the sucker rod in one direction but which effectually prevents relative rotation thereof in the opposite direction. The 25 purpose of this feature of the invention is to prevent unscrewing of the sections of the sucker rod due to the natural rotation thereof during operation and at the same time to 30 provide for rotation of the sucker rod by the operator of the well when the same is desired.

A still further object of the invention is to provide a device of this character which 35 may be readily applied to the present construction of sucker rods employed in oil wells without in any manner altering the structure thereof.

An additional object of the invention is to 40 provide a device of this character which is simple in its construction and operation, durable in service, and a general improvement in the art.

These and other objects I accomplish by 45 the construction and arrangement shown in the accompanying drawings wherein for the purpose of illustration is shown a preferred embodiment of my invention and wherein like reference characters designate like parts throughout.

In the drawings:

Figure 1 is a vertical sectional view taken through a sucker rod coupling constructed in accordance with my invention; and

55 Figure 2 is a similar view showing the po-

sition assumed by the sections of the coupling during a down stroke.

Referring now more particularly to the drawings, the numeral 10 indicates a cylinder of the same or slightly larger diameter 60 than the usual diameter of the sucker rod. The bore 11 of the cylinder is restricted at the lower end, as indicated at 12, to form an upwardly directed shoulder 13. The cylinder is provided with internal screw-threads 65 throughout substantially its entire length and engaged with these screw threads at the upper end of the cylinder is a coupling member 14 by means of which the upper end of the cylinder may be connected to the 70 lower end of the sucker rod section 15. Slidably directed through the restricted bore 12 at the lower end of the cylinder and projecting upwardly into the cylinder is a shaft 16, the lower end of which is formed with a 75 coupling member 17 adapted to connect the shaft to the upper end of a second sucker rod section, indicated at 18. The coupling members 14 and 17 may be of any desired construction and the coupling member 17, 80 for a purpose hereinafter rendered obvious, has its upper face spaced from the lower face of the cylinder 10.

Mounted in spaced relation within the cylinder 10 and having threaded engagement 85 with the walls thereof, are annular stop members or supports 19, these supports being in spaced relation and the lowermost support 19 being in similarly spaced relation to the shoulder 13 formed by the restriction 90 of the bore of the cylinder 10. Secured to the shaft 16 intermediate each pair of supports 19 and intermediate the lowermost support 19 and the shoulder 13 are nuts or flat disks 20. Upon the upper surface of each of the supports 19 and upon the shoulder 13 is disposed an anti-friction bearing 21 composed of a pair of race plates 22 having anti-friction balls 23 disposed therebetween. Upon the upper surface of each of the anti-friction bearings 21 rests a compression spring 24 of a desired length and a bumper member 25. These bumper members are of less height than the springs 24 and loosely surround the shaft 16. The 100 bumpers may be formed of any desired material but are preferably formed of relatively stiff rubber which will, while yielding slightly, form a positive limit for the movement of the shaft, as hereinafter more fully 105

110

set forth. Upon the upper surface of each of the nuts 20 are disposed springs 26 similar to the springs 24, and bumper members 27 similar to the bumper members 25.

5 The upper end of the shaft 16 is squared, as indicated at 28, and is slidably directed through a ratchet disk 29 disposed between the uppermost support 19 and a collar 30 secured within the cylinder 10 above and in spaced relation to the uppermost support 19. The disk 29 is provided upon its upper surface with ratchet teeth which coact with pawls 31 carried by the collar 30. The shaft 16, and more particularly the squared portion 28 thereof, is rotatable in the collar 30 and the uppermost support 19, but rotation of the shaft in a clockwise direction with relation to the collar and support is prevented by the ratchet and pawl engagement of the disk and collar, thus preventing unscrewing of the sections of the shaft, since it is necessary that the shaft be turned in a clockwise direction to unscrew a right hand threaded engagement if the rotation be imparted from the lower end.

25 In the operation of my device, when the device is stationary the weight of the lower sections of the sucker rod compresses the springs 24 until the nuts 20 of the shaft 16 come into engagement with the bumper members 25. Since these bumper members and spring rest upon the anti-friction bearings 21, the weight of the lower end of the sucker rod is supported on the anti-friction 30 bearings and accordingly may rotate freely. When the rod is moved in a down stroke, the inertia of the lower end of the rod will cause the shaft 16 to move upwardly within the cylinder bringing the springs 26 into engagement with the supports 19 where they are compressed until the movement is limited by the bumper members 27. When the direction of movement is reversed, the springs 24 take the shock until relieved by 35 the bumper members 25. If it is desired for any reason to rotate the sucker rod, this may be accomplished by placing a wrench upon the upper end of the sucker rod and rotating the entire sucker rod. It will likewise be obvious that by application of the wrench at the upper end of the sucker rod or above the coupling member, the sucker rod may be disjointed, since rotation in a clockwise direction from above will disconnect the sections regardless of the ratchet provided.

50 A single coupling such as described will ordinarily do in a well of average depth, though more may be supplied if it is desired. In very deep wells, say for example 3000

60 foot wells, the use of a plurality of connections is desirable since it eliminates the necessity of employing a large cylinder and heavy springs and bumpers.

65 From the foregoing it is believed to be obvious that a sucker rod coupling constructed in accordance with my invention is particularly well adapted for the purpose for which it is intended for the reason that it prevents jarring of the machinery during change of motion of the sucker rod and at 70 the same time prevents accidental unjointing of the sucker rod by the natural rotation through the engagement of the valve carried thereby with the working valve and permits unjointing of the rod from the upper end 75 when this is desired. It will furthermore be obvious that the construction hereinbefore set forth is capable of many changes and modifications without departing from the 80 spirit of my invention and I accordingly do not limit myself thereto except as herein-after claimed.

I claim:—

1. In a sucker rod coupling, a cylinder 85 adapted for engagement with one of adjacent ends of a sucker rod string, a shaft having its end extending into the opposite end of the cylinder and adapted for engagement with the other of the adjacent ends of the string, spaced supports disposed within said cylinder, nuts carried by said shaft intermediate each pair of spaced supports, springs extending intermediate said nuts and the adjacent supports, and abutment members limiting the compression of said springs during movement of the shaft within the cylinder.

90 2. In a sucker rod coupling, a cylinder adapted for engagement with one of adjacent ends of a sucker rod string, a shaft having its end extending into the opposite end of the cylinder and adapted for engagement with the other of the adjacent ends of the string, spaced supports disposed within said cylinder, nuts carried by said shaft intermediate each pair of spaced supports, springs 95 extending intermediate said nuts and the adjacent supports, abutment members limiting the compression of said springs during movement of the shaft within the cylinder, and an anti-friction bearing disposed upon the upper surface of each of said supports 100 and supporting the weight of the shaft attached portion of the string when the string 105 is elevated.

110 In testimony whereof I hereunto affix my signature.

REGINALD E. COX.
